P. DEMETROPOULAS

ARTICLE OF FURNITURE

Filed Nov. 15, 1924

Inventor
Peter Demetropoulos
By *Charles W. Niles* Atty

UNITED STATES PATENT OFFICE.

PETER DEMETROPOULAS, OF CHICAGO, ILLINOIS.

ARTICLE OF FURNITURE.

Application filed November 15, 1924. Serial No. 750,060.

To all whom it may concern:

Be it known that I, PETER DEMETROPOULAS, a citizen of the Kingdom of Greece, who has declared his intention of becoming a citizen of the United States, residing at Chicago, Cook County, Illinois, have invented certain new and useful Improvements in an Article of Furniture; and I do hereby declare that the following is a full, clear, and exact description of the same, reference being had to the accompanying drawings, and to the numerals of reference marked thereon, which form a part of this specification.

15 This invention relates to controlling mechanism for alarm clocks and comprises means attached to the back of the clock and operable at a distance, for shifting the alarm switch.

20 The invention consists of the novel structure and combinations hereinafter described and more particularly pointed out and defined in the appended claim.

In the accompanying drawings which illustrate one embodiment of this invention and in which similar reference numerals refer to similar features in the different views.

On the drawings:

Figure 1 is a front elevational view of the clock mounted upon a pedestal.

Figure 2 is a side elevational view of the clock and pedestal.

Figure 3 is a rear elevational view of the clock per se.

35 As shown on the drawings:

In referring to the drawing, it will be observed that the clock 1 may be of any conventional type having an alarm switch lever 2 projecting through a slot in the rear thereof. This clock is sustained upon an ornamen-

tal pedestal 3 having a circular intermediate shelf or table 4 and electric light bracket 5 so that the lights will be located upon opposite sides of the clock.

It is frequently desirable to shut off the alarm in such a clock from a sitting or inclining position. It might be desirable to shut off the alarm or set the same when a person is in bed. Accordingly I have devised means for controlling the alarm from a short distance.

In referring to Figure 3, it will be observed that I have pivoted an operating lever 6 intermediate its ends upon the back of the clock. This lever has a vertical arm 7 which is attached to the switch lever 2 for controlling the alarm. A cable 8 is attached to each end of the lever 6. By pulling upon the proper cable the alarm will be shut off, and by pulling upon the other cable, the alarm may be set to ring.

I am aware that numerous details of construction may be varied through a wide range without departing from the principles of this invention, and I therefore do not purpose limiting the patent granted hereon, otherwise than necessitated by the prior art.

I claim as my invention:

In a device of the character described, an alarm clock, a support therefor, an alarm switch in said clock, an operated lever pivoted upon the back of the clock and having a vertical arm attached to said switch lever and oppositely disposed horizontal arms, and cables attached to the ends of said horizontal arms for shifting said operated lever to control the position of said switch lever.

In testimony whereof I have hereunto subscribed my name.

PETER DEMETROPOULAS,
